UNITED STATES PATENT OFFICE.

FRANKLIN N. CONANT, OF NEWBURYPORT, MASSACHUSETTS, ASSIGNEE TO CHASE-SHAWMUT COMPANY, OF NEWBURYPORT, MASSACHUSETTS, A CORPORATION OF MAINE.

RENEWABLE FUSE.

1,299,132.

Specification of Letters Patent.

Patented Apr. 1, 1919.

Application filed March 9, 1918. Serial No. 221,344.

To all whom it may concern:

Be it known that I, FRANKLIN N. CONANT, a citizen of the United States, and a resident of Newburyport, county of Essex, and State of Massachusetts, have invented an Improvement in Renewable Fuses, of which the following is a specification.

My invention relates to inclosed fuses of the cartridge type, having knife-blade contact blades and particularly has, as an object, to provide a structure of such strength that repeated renewals can be made with a minimum of deterioration, and so simple and easy to assemble that any unskilled user can renew the fusible element easily, accurately and without tools.

My invention has other advantages which will be apparent to those skilled in the art, from the mere examination of the drawings in connection with the specification, not the least of which advantages is the fact that a person skilled in the manufacture of such articles can make the structure at a remarkably low cost, considering the massive character of all portions bearing a strain.

In the drawings, Figure 1 shows in side elevation and partial section a fuse made in accordance with my invention.

Fig. 2 is an end view of the ferrule showing the inwardly extending flange.

Fig. 3 is a plan view of one of the terminal plates.

Fig. 4 is a plan view of the plate which locks the terminal plate against rotation.

Fig. 5 is a plan view of a washer.

Fig. 6 is a plan view of the plate forming the slotted end portion of the end cap.

Fig. 7 is a perspective view of the end cap, with the slotted end plate removed.

Fig. 8 is a perspective view of a modification of the tubular portion, having the inwardly extending flange.

Fig. 9 is a plan view of a fusible element embodying my invention.

In this specification, the word fuse is used to include not only the fusible element, but its terminals and the casing and end caps, in short, the entire structure, as is the custom in the trade.

1 represents the tubular fiber casing and 2 a metal tube or ferrule permanently fastened thereto by screws 3 or other suitable fastenings, said tube being exteriorly screw threaded and having an inwardly extend-

ing flange 4, which engages and holds the 55 knife-blade contact plates 5 against movement, both longitudinal and rotational, when the end cap is in place, as hereinafter pointed out. This inwardly extending flange 4 (see Fig. 2) has a central opening 60 which is wide enough one way to receive the full width of the terminal contact blade 5, while at another portion the opening is too small to receive the entire width of the terminal blade 5 against longitudinal movement, as hereinafter described. By preference I make the opening in the inwardly extending flange 4 circular except for diametric notches 7 at one portion. The notched portion 7 should provide an opening to receive the entire width of the blade 5, while the opening elsewhere is narrower than the main body of the blade 5, but slightly wider than the blade at the notched portion of said blade. The terminal blade 75 5 is provided with notches 8 in its edge, preferably two oppositely placed notches, and it will readily be seen that the terminal blade may be slipped through the notches 7 in the flange 4 of the ferrule 2, and when 80 turned a quarter circle the walls 6 of the flange will enter the notches 7 and the knife-blades 5 will be held very firmly against longitudinal movement by the abutments 6.

In order to lock the knife-blade plates in this position against rotation, I provide a plate 9, having a slot 10, which fits the knife-blade 5 and is provided with a protuberance or protuberances 11 which enter the 90 notches 7 of the inwardly extending flange, as shown in Fig. 1, and are held firmly against rotation by the walls thereof. Means for preventing venting of the metal vapor formed when the fuse blows, of any desired 95 character, may then if desired be placed around the knife-blade, for instance, a slotted leather washer 12. An end cap 13, screw threaded, and preferably having a separate slotted plate 14 which forms the end portion is then screwed over the tube 2, thus completing the assembling and holding the parts firmly in place against movement, either longitudinal or rotational. The fusible element may be fastened to the terminals 100 in any desired manner and may consist of any proper material or of any desired configuration. In the drawings I have shown a

slotted zinc strip 16, attached by a screw 17 to the terminal blade 5 which I believe to be new and useful.

In Fig. 8 I have shown a modification of my invention, in which, in place of a ferrule 2 I use a tubular metal portion 18, permanently attached to the interior of the fiber casing, extending beyond the same endwise, the endwise extension 19 being as heretofore described. The advantage of this modification is that it makes it practicable to use a much heavier and stronger thread, without increasing the width of the total structure.

15 When the fuse containing my invention has been blown, the end caps 18 are unscrewed and the terminals turned a quarter turn, so as to occupy the notched portion of the flanges 8, when the terminals can be withdrawn. The fuse case should then be carefully cleaned, to remove, so far as possible, the remnants caused by the previous blowing of the fuse. A new fusible element is then attached between the terminals in any suitable manner, as by unscrewing the screws 16, scraping the fragments of the fusible element from the terminal, and screwing on a new fusible element.

This combined structure, namely, the two terminals with the fusible element between them, is then threaded through the notches 7 of the inwardly extending flange until the notched portion 8 of the terminal blade registers with the notches 7 of the flange 4. 35 The structure is then given a quarter turn and one of the plates 9 is placed over one of the terminal plates and its protuberances, 11 are caused to register with the notches 7 of the inwardly extending flange 4. The leather washer 12 and the plate 14 are then placed in position and the end cap screwed on, thus completing the assembling of one end of the fuse and the other end is then assembled in like manner. The interior of 45 the fusible case may, if desired, be filled with the usual fuse filling material, such as ground sulfate of calcium, slaked lime, or other suitable material, either in whole or in part, in the usual manner.

50 The fusible element 16 is formed of a strip of zinc or other easily fusible material and has a plurality of longitudinal slots 20 therein which divide the fusible element into a plurality of easily fusible portions 21. 55 Said slots 20 are relatively staggered and said easily fusible portions 21 are thereby formed with more easily fusible portions 22 which are staggered in respect to each other to thereby separate the fusing portions when 60 the fuse blows.

These readily fusible portions are very long compared to the entire length of the fuse, in fact, the slotted portion of the fusible element is longer than the unslotted portion of the fusible element, which is not con-

nected with the terminal, but, nevertheless, a substantial unslotted portion is preserved between the terminal blade and the slotted portion of the fusible element.

I claim:

1. In an electric fuse, an inclosing casing having a terminal portion, said terminal portion having an inwardly extended flange with a recess therein, a terminal plate extended in said casing in detachable engagement with said flange for restraint against longitudinal movement in said casing, an end plate engageable with said terminal plate having a projection engageable with the recess in said flange to prevent rotational movement of said terminal plate, and an end cap detachably connected with said terminal portion to lock said terminal blade in position.

2. In an electric fuse, a cylindrical fiber case having exteriorly threaded metal ferrules at each end thereof, said ferrules having inwardly extending flanges with diametric notches therein adapted to receive a terminal blade, a terminal blade having opposite notches in the edge thereof adapted to fit the inwardly extending walls of said flange and be held thereby against longitudinal movement, a locking-plate adapted to engage said terminal blade and said flange and prevent rotational movement of said terminal blade, and an end cap interiorly screw-threaded and adapted to lock said plate and terminal blade in position.

3. In an electric fuse, a shell or case comprising a tubular body of insulating material and metal tubes attached to the end thereof, said metal tubes being exteriorly screw-threaded and adapted to receive interiorly screw-threaded end caps thereon, a flange extending inwardly from each metal tube, having an opening therein adapted to receive a terminal blade and provided with an abutment adapted to fit notches in the terminal blade and hold said terminal blade against movement longitudinal of the fuse case, terminal blades having notches therein adapted to engage said abutments, metal plates having a slot therein adapted to fit said terminal blades and having engaging portions adapted to enter and engage said flanges and prevent rotation of said plates and terminal blades, and end caps adapted to be screwed upon said metal tubes and hold the locking-plate in position, substantially as described.

4. In an electric fuse or cut-out, a shell or case comprising a tubular body and metal tubes attached to the ends thereof, said metal tubes being exteriorly screw-threaded and adapted to receive interiorly screw-threaded end caps thereon, a flange extending inwardly from each metal tube, having an opening therein adapted to receive a terminal blade at one portion of said opening and

at another portion being provided with an abutment adapted to fit notches in the terminal blade and hold said terminal blade against movement longitudinal of the fuse case; a terminal blade having notches therein adapted to engage said abutment, a metal locking plate having a slot therein adapted to fit said terminal blade and protuberances adapted to enter a wide portion of said flanges and engage the walls of said flanges so as to prevent rotation of said plate and the terminal blade, and an end cap adapted to be screwed upon said metal portion and hold the locking-plate in position, substantially as described.

5. A renewable fusible element for electric fuses consisting of a strip of readily fusible metal having a plurality of longitudinal slots therein forming a plurality of 20 readily fusible portions having their most fusible portions in staggered relation.

6. A renewable, fusible element for electric fuses consisting of a strip of a fusible metal having a plurality of readily fusible 25 portions arranged in staggered relation.

7. A renewable fusible element for electric fuses consisting of a strip of fusible metal having a plurality of readily fusible portions arranged in staggered relation, said readily fusible portions being longer than the combined integral portions of the fusible element between its terminals.

8. An inclosed electric fuse of the cartridge type comprising an inclosing casing of fiber having terminal contact portions 35 and a fusible element therefore comprising a strip of fusible material having a plurality of longitudinal slots therein forming a plurality of readily fusible portions having their most fusible portions in staggered 40 relation, connected to said terminal contact portions.

In testimony whereof I have signed my name to this specification in the presence of two subscribing witnesses.
